SAND SEPARATOR

Application filed November 24, 1924. Serial No. 751,914.

This invention relates to devices for effecting the separation of substances of different specific gravities. More particularly, the invention relates to a device for separating sand from river and other sand carrying water, so as to obtain water substantially free of sand for most practical commercial purposes. One particular use to which the water thus obtained has been put is the flushing 10 out of water turbines to prevent disintegration by the sand of contacting parts.

The object of the present invention is to provide an improved sand separator in which the sand carrying water introduced therein is subjected to a swirling action to separate therefrom the heavier sand particles, in which device the swirling action is produced by the pressure of the sand carrying water introduced therein, so that the separator is exceedingly economical to operate; in which device the pressure of the separated water controls the discharge of the separated sand; and which separator is strong and durable and of simple and inexpensive construction 25 not likely to get out of order in service.

In the drawing, which represents one suitable embodiment of the invention, Fig. 1 is a central vertical sectional view of the present improved sand separator; and Figs. 2, 3, 30 4, and 5 are, respectively, cross-sectional views on the lines 2—2, 3—3, 4—4, and 5—5, Fig. 1.

The separator illustrated in the drawing comprises a sectional metal casing, consisting of a substantially cylindrical intermediate or main body section 1, a dome shaped top or cover section 2, and a similarly shaped bottom section 3. These three sections are provided with suitable flanges, the flanges of 40 adjacent sections being removably secured together, such as by the bolts 5.

The bottom casing section is provided with suitable supporting legs 6, which in the present embodiment rest upon a suitable foundation 45 7. This foundation is provided with an opening 8 beneath the central portion of the casing to receive the casing 9 for the separated sand, which casing is bolted or otherwise suitably secured to the bottom casing section 3. 50 Communicating with the foundation opening

8 is a side foundation passage 10 into which the separated sand is discharged from casing 9, as will later appear.

Suitably secured by the bolts 5 between the adjacent flanges of the intermediate and the cover casing sections is the outwardly extending flange 15 of a depending, hollow member 16 of substantially cone shape, which is centrally disposed within the intermediate casing section. An annular space or chamber 55 17 of gradually increased width from top to bottom is provided between said casing section and this cone-shaped member, which chamber merges with the substantially conical shaped chamber 18 of the bottom casing 60 member and forms, in effect, a single separating chamber.

The intermediate casing section is provided near its upper end with a tangentially disposed tubular extension 20, preferably formed integral therewith, through which the sand carrying water is introduced under pressure into the chambers 17—18 just referred to. Due to the tangential disposition of this water inlet 20, the sand carrying 70 water introduced into the separator is given a swirling action in the annular chamber 17, with the result that the sand particles, being heavier than water, are thrown outwardly against the intermediate casing section, and finally pass down into the chamber 18 75 of the bottom casing section. The water closely surrounds the outer surface of the conical-shaped member 16, travels down therealong, enters the bottom opening 21 80 thereof, passes upwardly through the chamber 22 of said member and the chamber 23 of the top cover section, and then passes out through the outlet port 24 in said last named section, the pressure of the incoming sand carrying water effecting this travel or movement of the water from which the sand has been separated.

The separated sand in the chamber 18 of the bottom casing section passes through 95 a discharge port 25^a in a tubular member 25 mounted in aligned openings in the bottom of casing section 3 and the adjoining sand casing 9 and is delivered at relatively great velocity into the annular passage 26 of said 100

sand casing. In order to reduce the velocity of the sand discharged into said annular chamber, the bottom portion thereof is of a substantial trough shape, as at 27, Fig. 1. 5 From this chamber, the sand passes through a central passage 28 extending downwardly and outwardly and discharging into the side foundation passage 10.

In order to control the passage of the separated sand through the discharge port 25^a into the sand receiving casing 9 and to insure the travel of the substantially pure water up through the conical-shaped member 16, a hollow spherical member 35 is arranged within 15 the chamber 18 of the bottom casing section. Said member is provided at its bottom with a conical shaped portion 36 provided with one or more sand discharge passages 37, one being here shown. This spherical member is 20 adjustably mounted upon the lower end of a vertically disposed spindle 38 extending through the conical-shaped member 16 and the cover casing section 2, being suitably supported at its upper end in bearings 39 and 40, 25 respectively secured within and mounted upon said cover section. The lower end portion of said spindle is supported or centered by the radially extending internal web members 42 of member 16. Within the chambers 30 22 and 23 of the conical-shaped member 16 and the cover casing section 2, said spindle is provided with a plurality of radially extending blades or vanes 45, four being here shown. The water, from which the sand has 35 been separated, in travelling through said chambers to the outlet 24 thereof strikes these vanes and causes the rotation of the spindle and hence the rotation of the conical shaped portion 36 of the spherical member 35, in 40 which conical shaped portion is the sand discharge passage 37.

The discharge of sand through the passage 25^a of the tubular member 25 may also be controlled by the conical-shaped valve 48 45 co-operating with the lower end of the said passage. Said valve is mounted upon the upright stem 49 adjustably mounted in the sand receiving casing 9, as by the threaded connection and lock nut shown wherein the 50 vertical position of the valve is adjusted by loosening the locknut and turning the shaft by its lower projecting end, which is squared for the purpose.

What we claim is:

55 1. A sand separator, comprising a casing having an inlet opening for the introduction of a physical mixture of sand and water under pressure, means within said casing for co-operating with the flow of said mixture for effecting separation of said substances, and means controlled by the flow of one separated substance for controlling the discharge of the other separated substance.

65 2. A sand separator, comprising a casing having an inlet opening for the introduc-

tion of sand and water together under pressure, means within said casing for effecting separation of said substances from each other, separate outlets for the sand and water, and means controlled by the flow of the separated water for regulating the discharge 70 of the separated sand through its outlet.

3. A sand separator, comprising a casing having an inlet opening for the introduction of sand and water together under pressure, means within said casing for effecting separation of said substances from each other, separate outlets for the sand and water, and rotary valve means controlled by the flow of the separated water for regulating 80 the discharge of the separated sand through its outlet.

4. A sand separator, comprising a casing having an inlet opening for the introduction of sand and water together under pressure, means within said casing for effecting separation of said substances from each other, separate outlets for the sand and water, a rotary valve for controlling the discharge 85 of the separated sand through its outlet, and a spinner actuated by the flow of the separated water for controlling said valve.

5. In a sand separator, a casing having a tangential water inlet, a water outlet, and a central restricted outlet for separated sand, 95 said separator being adapted to receive water under pressure, separate the sand therefrom, and discharge the separated sand at high velocity through said restricted outlet, and means for reducing the velocity of the sand discharged from said outlet, said means comprising a conical deflector arranged below and concentric with said outlet, and an annular trough arranged about said deflector to receive the discharge thereof and direct the same radially inwardly.

6. A sand separator, comprising a casing having an inlet opening for the introduction of sand and water together under pressure, means within said casing for effecting separation of said substances from each other, separate outlets for the sand and water, a rotary valve for controlling the discharge 110 of the separated sand through its outlet, and a spinner actuated by the flow of the separated water for rotating said valve, said rotary valve having on its periphery a longitudinal groove.

7. In a sand separator, a casing having a cylindrical body portion terminating downwardly in a conical portion, a tubular member of substantially cone shape concentrically disposed with said cylindrical portion to divide the interior thereof into an annular passage of downwardly increasing sectional area and a central passage of upwardly increasing sectional area, sealing means between the upper extremities of said casing and tubular member, a cover member for the upper extremity of said tubular member, said 125

cylindrical body portion having a tangential water inlet near its upper end, said conical portion having a central restricted sand outlet aperture and said cover member having
5 a water outlet.

In testimony whereof we hereby affix our signatures.

KARL A. ENZ.
